HAMMER CONTROL MECHANISM

Donald J. Patterson, Los Angeles, Calif., assignor
to Simplex Time Recorder Co., Gardner, Mass.,
a corporation of Massachusetts

Application October 23, 1944, Serial No. 559,967

6 Claims. (Cl. 234—43)

1

This invention relates to recorders by which a time record may be stamped on a payroll card or other desired sheet.

It is the general object of my invention to provide improved means for preventing the making of more than one impression on a record card or sheet at a single presentation thereof.

To the accomplishment of this general object, I provide novel means effective to open the hammer circuit after a single impression has been made, and to hold the circuit open until the card has been withdrawn a substantial distance from its stamping position.

My invention further relates to arrangements and combination of parts which will be herein-after described and more particularly pointed out in the appended claims.

A preferred form of the invention is shown in the drawing, which is a diagrammatic view illustrating the construction and operation of my improved control mechanism.

In the drawing I have shown portions 10 of a card guide in which a card C is inserted from the top in the usual manner and is moved downward until it engages a card rest or abutment 12. The abutment 12 is pivoted at 13 to a lever 14, which in turn is pivoted at 15 to a plate 16.

The card support 12 and plate 16 may constitute a movable unit which is shiftable vertically to position records in desired spaces on the card C, but this movable mounting of the support 12 and plate 16 forms no part of my present invention and is not illustrated herein.

A spring plate 20 is mounted on a block 21 fixed on the plate 16, and a second spring plate 22 is similarly mounted below the block 21, which block is of non-conducting or insulating material. The plate 20 has contacts 30 and 31 on its under face and the plate 22 has a contact 32 on its upper face. Another contact 34 is mounted on a fixed insulating block 35 and is positioned for engagement by the contact 31. The lever 14 has a non-conducting end plate 37 engaging the spring plate 20.

A line wire L is connected to the spring plate 20 and a second line wire L' is connected by a wire 40 to a relay solenoid 41 and by a branch wire 42 to a hammer solenoid 43. The solenoid 41 is also connected through a wire 44 to the contact 34 and by a branch wire 45 to a spring plate 46 mounted on a fixed insulating block 47.

The spring plate 46 is connected by a link 50 to the plunger 51 of the relay solenoid 41. The plunger 51 is normally drawn downward by a spring 52. The plate 46 has a double contact

2

55 engaging a lower contact 56 when in normal position and an upper contact 57 when the solenoid 41 is energized and the plunger 51 is moved upward. The hammer solenoid 43 is connected by a wire 60 to the lower contact 56, and the spring plate 22 is connected by a wire 61 to the upper contact 57.

The plunger 70 in the solenoid coil 43 is connected to actuate any suitable hammer mechanism, such as is shown, for instance, in prior Patent No. 2,102,771, issued December 21, 1937. Such mechanism forms no part of the present invention.

Having described the details of construction and the electrical connections of my improved control mechanism, the operation thereof is as follows:

The card C is inserted in the guides 10 and is pushed downward to engage the card support 12 and move the support a limited distance downward after such engagement. Such final downward movement swings the lever 14 and depresses the spring plate 20. The contacts 30 and 32 are first engaged, after which the contacts 31 and 34 are engaged.

Engagement of the contacts 31 and 34 completes a circuit from the line wire L through contacts 31 and 34, wire 44, wire 45, spring plate 46, contacts 55 and 56 and wire 60 to the hammer solenoid 43, which in turn is connected through branch wire 42 and wire 40 to the line wire L'. The hammer solenoid is thus energized and an impression is stamped on the card.

A circuit is also closed through the contacts 31 and 34, wire 44, holding solenoid 41 and wire 40 to the line wire L', thus energizing the solenoid 41. This moves the double contact 55 to break the hammer circuit through the contact 56 after a single blow, and to engage the upper contact 57. A holding circuit is completed by this latter engagement, the circuit being from the line wire L through contacts 30 and 32, spring plate 22, wire 61, contacts 57 and 55, spring plate 46 and wires 45 and 44 to the holding solenoid 41 and by wire 40 to line wire L'. This maintains the solenoid 41 active and at the same time holds the hammer solenoid 43 inoperative, even if the contacts 31 and 34 remain closed. A single blow only of the hammer mechanism can thus be delivered.

The hammer solenoid circuit remains broken until the card C is lifted far enough to allow separation of the contacts 30 and 32, which obviously involves prior separation of the contacts 31 and 34. Consequently, a second impression

cannot be made on the card C until the card has been lifted far enough to permit the card support 12, lever 14 and spring plate 20 to return to their original raised positions, and until downward pressure is thereafter applied a second time to the card.

I thus effectually prevent the accidental making of two impressions on a card, as has heretofore frequently taken place when a card was somewhat loosely held and was very slightly raised from stamping position. With the present construction, a substantial and definitely intended raising of the card is necessary before a second impression can be made.

Having thus described my invention and the advantages thereof, I do not wish to be limited to the details herein disclosed, otherwise than as set forth in the claims, but what I claim is:

1. In a time recorder, a hammer-actuating solenoid, a circuit therefor, a holding solenoid effective to break said hammer circuit, a circuit for said holding solenoid, and a card-depressed switch member having a first contact in the holding solenoid circuit only and a second contact in the holding solenoid circuit and in the hammer solenoid circuit jointly, said two contacts being closed and opened successively by said switch member, with the contact which is in the holding solenoid circuit only closing first and opening last.

2. In a time recorder, a hammer-actuating solenoid, an operating circuit therefor, a holding solenoid effective to break said hammer circuit, an operating circuit for said holding solenoid, and a single card-operated switch member effective by a continued downward movement to close the holding circuit at one point and to close the holding solenoid and hammer solenoid circuits at a second point, said holding solenoid being immediately operative to break the hammer solenoid circuit after a single impression, and said holding solenoid circuit being maintained until the card operated switch member is returned substantially to initial and fully raised position.

3. In a time recorder, a hammer-actuated solenoid, an operating circuit therefor, a holding solenoid effective to break said hammer circuit, an operating circuit for said holding solenoid, and a card-operated member having a contact in said holding solenoid circuit only and having an additional contact in said holding solenoid circuit and in said hammer solenoid

circuit jointly, said contacts being so positioned and connected that the holding solenoid circuit is closed with the hammer solenoid circuit and is maintained closed after said hammer solenoid circuit is broken and until said card-operated member is returned substantially to initial and substantially raised position.

4. In a time recorder, a control system comprising a card-actuated switch member having a substantial operating movement, a hammer-actuating solenoid, a circuit therefor, a holding solenoid effective to break said hammer solenoid circuit, a circuit for said holding solenoid, said circuits being closed in parallel, and a second switch member actuated by said holding solenoid to break said hammer solenoid circuit and to simultaneously close the holding solenoid circuit through a parallel connection, said holding solenoid circuit being thereafter opened during the first part of the return movement of said card-actuated switch member and said holding solenoid circuit being broken at the parallel connection during further return movement of said card-actuated switch member to initial raised position.

5. In a time recorder, a hammer-actuating solenoid, a circuit therefor, a holding solenoid effective to break said hammer circuit, a circuit for said holding solenoid, and a card-depressed switch member having a first contact in the holding solenoid circuit only and a second contact in the holding solenoid circuit and in the hammer solenoid circuit jointly, both circuits being closed by extreme downward movement of said switch member, said hammer solenoid circuit being thereafter opened by said holding solenoid while said switch member remains fully depressed, and said holding solenoid circuit remaining closed and said hammer solenoid circuit remaining open until said switch member is restored substantially to its initial raised position.

6. In a time recorder, a hammer-actuating solenoid, a circuit therefor, a holding solenoid effective to break said hammer circuit, a circuit for said holding solenoid, and a card-depressed switch member operative to close both circuits on extreme downward movement and operative to maintain the holding solenoid circuit closed until said switch member returns substantially to initial raised position.

DONALD J. PATTERSON.
